UNITED STATES PATENT OFFICE.

FRED A. BERRY, OF LOS ANGELES, CALIFORNIA.

DESIGN FOR A MEDALLION, BADGE, WATCH-FOB, WATCH-CHARM, RING, SCARF-PIN, BROOCH, BUTTON, OR SIMILAR ARTICLE OF JEWELRY.

47,983.

Specification for Design.

Patented Oct. 19, 1915.

Application filed August 10, 1915. Serial No. 44,845. Term of patent 3½ years.

To all whom it may concern:

Be it known that I, FRED A. BERRY, a citizen of the United States, residing at Los Angeles, in the county of Los Angeles and State of California, have invented a new, original, and ornamental Design for a Medallion, Badge, Watch-Fob, Watch-Charm, Ring, Scarf-Pin, Brooch, Button, or Similar Article of Jewelry, of which the following is a specification, reference being had to the accompanying drawing, forming part thereof.

The figure is a plan view of a button, showing my new design.

I claim:

The design for medallion, badge, watch-fob, watch-charm, ring, scarf-pin, brooch, button, or similar article of jewelry, as shown.

FRED A. BERRY.
